UNITED STATES PATENT OFFICE

IVAN S. CARPENTER, OF DENVER, COLORADO, ASSIGNOR TO GARDNER-DENVER COMPANY, OF DENVER, COLORADO, A CORPORATION OF DELAWARE

LUBRICATING APPARATUS

Application filed June 6, 1930. Serial No. 459,545.

In apparatuses such as drill sharpeners, considerable difficulty is experienced in effectively lubricating the same. The object of the present invention is to provide a means by which the motive fluid that is distributed to the various parts, is caused to act as a carrier for the lubricant, so that the moving parts to which the motive fluid is supplied, will thereby be also supplied with lubricant.

In the accompanying drawings, there is disclosed an embodiment of the invention applied to a drill sharpener.

In said drawings:

15 Figure 1 is a view partly in elevation and partly in section of such sharpener, and showing the lubricating apparatus in elevation.

20 Figure 2 is a vertical sectional view diagrammatic in its character through the same.

Figure 3 is a detail vertical sectional view on an enlarged scale of the lubricator.

In the embodiment disclosed, a chambered base 4 is provided, the chamber 5 thereof forming a reservoir for motive fluid and for lubricant. Supported on this base are cylinders 6 and 7, in which are pistons 8 and 9. These pistons are connected by piston rods 10 with a movable holding die 11 that overlies a stationary coacting holding die 12. Obviously when motive fluid is supplied to the upper faces of the pistons 8 and 9, the die 11 will be moved downwardly toward the die 12, and the work, as for example, a 35 drill steel, placed between the dies, will be clamped thereby. As shown in Figure 1, a pneumatic dolly hammer 13 is mounted at one side of the dies and is adapted to operate in a well-known manner on the work held by the dies 11 and 12.

40 For the purpose of supplying fluid to the pistons 8 and 9, a passageway 14 leads from the upper portion of the chamber 5 to a valve chamber 15 mounted on one side of the upper cylinder 7. Leading from this valve chamber 15 are two passageways 16 and 17 that open respectively into the cylinders 6 and 7. Communication between the supply passageway 14 and the passageways 16 and 17 is controlled by a reciprocatory

spool valve 18 operating in the valve chamber 15 and actuated by a hand lever 19. A conduit 20, leading from the valve chamber 15, supplies motive fluid to the dolly hammer 13, as shown in Figure 2 and is controlled by a valve 21 whose stem 22 is actuated by the lever 19.

55 It is believed that the above sufficiently explains the structure for the purposes of the present invention. A more detailed exposition of the same will be found in the application for patent of L. E. Croft, Ser. No. 311,227, filed October 8, 1928.

Leading to the chamber or reservoir 5 at a point well above its bottom is a motive fluid supply pipe 23. This pipe has coupled thereto a head 24 adjacent to the base 4, said head having in its upper portion a passageway 25 through which the motive fluid flows on its way to the reservoir 5. This head furthermore has in its lower portion a socket 26 in communication with the lower portion of the reservoir 5 by a coupling 27. The head furthermore has a vertical bore 28 intersecting the passageway 25 and socket 26, the lower portion of the bore being enlarged to receive a threaded plug 29 provided with a pocket 30 in its upper end. This enlargement with the pocket 30 constitutes a well 31 into which the lubricant 35 may freely flow from the bottom of the reservoir 5. A vertical stem 32 is rotatably mounted in the bore 28 and has a vertical passageway 33 extending upwardly from its lower end to a transverse port 34 opening through the opposite sides of the stem in the passageway 25. The upper end of the stem has a bearing against an adjustable holding plug 35 threaded in the top of the head 24 and bearing against the 40 end of the stem. The stem is supported by a coiled spring 36 surrounding its lower end which is reduced, as shown at 37, the spring entering the cup 30 and bearing against the plug 29. It will be noted particularly by reference to Figure 3 that the lower end of the passageway 33 is freely open to the lubricant that enters the well.

45 With this structure, the motive fluid passing through the supply pipe 23 and there-

fore through the passageway 25 of the head 24 will cause the oil that is in the well 30 to rise through the passageway 33 and enter the fluid stream through the port 34, being 5 thereby atomized and flowing with the motive fluid (usually air) into the reservoir 5. Here the excess lubricant will be separated from the fluid and drop back into the body of lubricant in the lower portion of the 10 chamber 5, but the motive fluid will be sufficiently saturated so that it will flow through the supply conduit 14 to the valve 18 and lubricate the latter, and thence to the various instrumentalities of the apparatus. 15 There is of course always a body of oil in the reservoir 5 that will supply the well 31. As a consequence the moving parts of the apparatus will be better lubricated and yet excessive or unnecessary amounts of oil are 20 not employed.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the 25 30 advantages of the invention.

What I claim is:

1. In a metal working machine, the combination with a fluid operated work holder, a motive fluid and lubricant reservoir, a conduit 35 for conveying motive fluid from the reservoir to the work holder to operate it and a valve mechanism for controlling the conduit, of means for supplying motive fluid to the reservoir, and means for delivering lubricant from the motive fluid and lubricant reservoir into the motive fluid supply means.

2. In a metal working machine, the combination with a fluid operated work holder, a motive fluid and lubricant reservoir, a conduit 45 for conveying motive fluid from the reservoir to the work holder to operate it and a valve mechanism for controlling the conduit, of means for supplying motive fluid to the reservoir, and a lubricant atomizer having an intake in communication with the reservoir and an outlet delivering into the motive fluid supply means.

3. In a metal working machine, the combination with a chamber for the reception 55 of lubricant and fluid under pressure, a conduit for supplying fluid under pressure to the chamber, an atomizer having an intake in communication with the lubricant holding portion of the chamber, and an outlet 60 opening into the conduit, of an outlet from the chamber for the lubricant carrying fluid.

4. In a metal working machine, the combination with a chamber for the reception of lubricant and fluid under pressure, a conduit 65 for supplying fluid under pressure to the

chamber, a lubricant holding well supplied by the chamber, and a stem having a lubricant passageway with an inlet in the well, said stem extending into the conduit and the passageway having an outlet in said conduit. 70

5. In a metal working machine, the combination with a work holding apparatus including a chambered base, said base constituting a reservoir for motive fluid and for lubricant, a conduit for directing the motive fluid from the chamber to the work holding mechanism to operate the latter, valve mechanism controlling the conduit, a motive fluid supply conduit leading to the chamber, a lubricant well receiving lubricant from the chamber, and an atomizer stem having a passageway provided with an inlet end in the well and an outlet orifice in the motive fluid supply conduit. 75 80

In testimony whereof, I affix my signature. 85
IVAN S. CARPENTER.
